Des. 235,161
Patented May 20, 1975

235,161

PERFORMER KEYBOARD CONSOLE

Alfred Mayer, Morristown, N.J., and George Ipolyi, Plainview, N.Y., assignors to Ionic Industries Incorporated, Morristown, N.J.

Filed Dec. 14, 1972, Ser. No. 315,178

Term of patent 14 years

Int. Cl. D17—01

U.S. Cl. D56—2

FIG. 1

FIG. 2

FIG. 3

FIG. 4

FIG. 5

FIG. 1 is a top plan view of a performer keyboard console showing our new design;

FIG. 2 is a front perspective view on a smaller scale;
 FIG. 3 is a bottom plan view on a still smaller scale;
 FIG. 4 is a left side elevational view; and
 FIG. 5 is a rear elevational view.

A portion of the legs is cut away in FIGS. 3 through 5 for convenience of illustration.

We claim:

The ornamental design for a performer keyboard console, substantially as shown and described.
